United States Patent Office

Des. 197,516
Patented Feb. 18, 1964

197,516

BRASSIERE

Frances M. Smith, Bridgeport, Conn., assignor to La Resista, Inc., Bridgeport, Conn., a corporation of Connecticut

Filed Mar. 20, 1963, Ser. No. 74,061

Term of patent 14 years

(Cl. D20—4)

FIG. 1 is a front view of a brassiere, showing by new design;

FIG. 2 is a rear view thereof;

FIG. 3 is a front perspective view thereof as it appears in wearing position; and

FIG. 4 is a rear perspective view thereof as it appears in unfastened position.

I claim:

The ornamental design for a brassiere, substantially as shown.
